UNITED STATES PATENT OFFICE.

WILLIAM C. MUSCHENHEIM, OF NEW YORK, N. Y.

DESIGN FOR A DISH.

SPECIFICATION forming part of Design No. 35,232, dated October 29, 1901.

Application filed September 27, 1901. Serial No. 76,810. Term of patent 3½ years.

To all whom it may concern:

Be it known that I, WILLIAM C. MUSCHENHEIM, a citizen of the United States, and a resident of the city of New York, borough of Manhattan, in the county and State of New York, have invented and produced a new and original Design for a Dish, of which the following is a specification, reference being had to the accompanying drawings, forming part thereof.

Figure 1 is a plan view of a dish, showing my design; and Fig. 2 is a sectional elevation of the same:

The invention relates to dishes for serving oysters, clams, and the like on ice contained in the dish.

The design in its entirety consists of the annular body A, terminating at its upper end in the outwardly and upwardly flaring flange B, the said body appearing at its inside with an annular horizontally-disposed shoulder

C, located about midway of the depth of the body A and having its side C' merging gently with the curved inner face of the lower portion of the body, as plainly indicated in Fig. 2.

The leading feature of the design consists in the body terminating in the flange and appearing at the inside with a shoulder approximately midway the depth of the body.

Having described my invention, what I claim as new, and desire to secure by Letters Patent, is—

The design for a dish, as herein shown and described.

In testimony whereof I have signed my name to this specification in the presence of two subscribing witnesses.

WILLIAM C. MUSCHENHEIM.
